IRONING BOARD HEIGHT ADJUSTER

Joseph J. Mrofka, Massillon, Ohio

Application January 27, 1950, Serial No. 140,871

3 Claims. (Cl. 38—117)

1

This invention relates to improvements in ironing boards having foldable and collapsible stand or leg structure, the primary object of the invention being to provide simple and effective height adjusting means for such stand or leg structure whereby the ironing board can be readily adjusted to different heights to suit different users.

Another important object of the invention is to provide inexpensive but rugged height adjusting brackets adapted to be attached to existing stands or leg structure whereby an ordinary foldable or collapsible stand or leg structure can be readily and inexpensively converted for selective vertical adjustment and levelling of the ironing board.

Other important objects and advantageous features of the invention will be apparent from the following description and the accompanying drawings, wherein, merely for purposes of illustration herein, a specific embodiment of the invention is set forth in detail.

In the drawing:

Figure 1 is a side elevation of an ironing board having a foldably collapsible stand or leg structure equipped in accordance with the invention.

Figure 2 is a bottom plan view of Figure 1, with the stand or leg structure collapsed.

Figure 3 is an enlarged fragmentary bottom plan view of a hinged bracket and adjustable foot.

Figure 4 is a vertical longitudinal section taken therethrough on the line 4—4 of Figure 2; and,

Figure 5 is an enlarged perspective view of a rigid bracket and adjustable foot.

Referring in detail to the drawings, wherein like numerals designate like parts throughout the several views, the numeral 7 designates a substantially conventional ironing board having foldably collapsible stand or leg structure including a pair of laterally spaced legs 8 hinged to the underside of the board at one end as indicated at 9 and occupying substantially perpendicular positions when unfolded, as shown in Figure 1, and occupying horizontal positions along the underside of the board 7 when collapsed, as shown in Figure 2.

Pivots 10' traverse the legs 8 midway between their ends and carry at the inward sides of the legs 8 the rearward ends of forwardly converging leg bars 10, and inwardly thereof the forward ends of link bars 11.

The forward ends of the leg bars 10 are rigidly connected together by a transverse pivot 12 with the forward end of a forwardly declining brace

2

bar 13 pivoted on the pivot 12 between the leg bars 10. The upper end of the brace bar 13 is positioned between two blocks 14, and traversed by a pivot 15 which traverses the blocks and also traverses the elevated forward ends of forwardly declining and rearwardly converging bars 16. The rear ends of the bars 16 are connected to the forward and elevated ends of the link bars 11, whose rear ends are pivoted on the pivots 10' at the inward sides of the leg bars 8.

Vertically adjustable feet 17 for the perpendicular legs 8 comprise bracket plates 18, secured by suitable means, such as screws 19, to and vertically along the laterally inward sides of the lower end portions of the legs 8, the bracket plates terminating at their ends in right angular upper and lower ears 21 and 22, respectively, having vertically aligned threaded holes 23 formed therein. Threaded upwardly through the holes in both ears is a screw 24, with a lock nut 25 thereon between the ears 21 and 22 and arranged to be turned against an ear, such as the lower ear 22 to lock the screw in vertically adjusted position.

The lower end of the screw 24 is traversed by a pivot 26 which also traverses a sleeve or socket 27, loosely receiving the lower end of the screw and having a disk 28 on its lower end to supportably engage the floor 29, as shown in Figure 1. The pivoting of the foot element composed of the socket 27 and the disk 28 relative to the screw 24 makes the foot self-levelling.

A vertically adjustable foot 30 for the depressed floor engaging end of the forwardly declining leg member formed by the bars 10 comprises a plate 30' secured to the undersides of the bars 10, as by means of screws 31, rearwardly of a plane angular floor engaging surface 32 on the undersides of the bars 10, and a swingable plate 33 having its rearward edge hinged at 34 to the forward edge of the plate 30. In the operative position the plate 33 supportably engages the angulated surface 32, as shown in Figure 1, while in the folded position the plate 33 occupies the retracted position shown in Figure 4.

The plate 33 has a forward end portion 35 formed with a threaded hole 36 through which is threaded a screw 37 having thereon a lock nut 38 adapted to be turned against the top of the plate 33 to maintain a vertical adjustment of the screw 37. The lower end of the screw 37 carries a self-levelling foot element similar to that on the screws 24.

It will be understood from the foregoing that the ironing board 7 may be both levelled and elevated or depressed to the desired height by ver-

tical adjustment of the screws 24 and 37. In the cases that the foldable stand or leg structure is made of metal rather than wood, as contemplated in the illustrated device, it is obvious that the foot brackets can be bolted or welded in place instead of being attached with screws.

What is claimed is:

1. In a collapsible ironing board construction involving an ironing board and foldable leg structure, said leg structure including legs perpendicular when extended in operative position and declining leg means, vertically adjustable foot means secured to each of said perpendicular legs, said foot means comprising rigid brackets secured to the inner sides of said perpendicular legs and each bracket having vertically spaced ears, each of said ears having a screw hole therein, the screw holes in said ears being in alignment with each other, a screw threaded upwardly through said holes, a lock nut on said screw between said ears and arranged to engage one of said ears to lock a vertical adjustment of said screw, and a self-leveling floor engaging member on the lower end of said screw.

2. A height adjusting foot for the declining leg element of an ironing board comprising a first plate adapted to be secured to the underside of said leg element inwardly of the terminal end of said leg element, a second plate having the inward edge hinged to the outer edge of said first plate and arranged to be swung to supportably engage the underside of said leg element outwardly of said first plate and having an end portion opposite said hinged edge arranged to extend outwardly beyond the terminal end of said leg element, said end portion being formed with a threaded hole, a screw threaded upwardly through said hole, a lock nut on said screw adapted to be turned against said second plate to maintain a vertical adjustment of said screw, and a loosely pivoted self-leveling floor engaging mem-

ber on the lower end of said screw, said second plate being arranged to be swung away from said leg element when not in use to a position wherein said floor engaging member rests against said leg element inwardly of said first plate.

3. In a collapsible ironing board construction including an ironing board and leg structure foldably hinged thereon, said leg structure comprising declining leg means having a depressed end, vertically adjustable foot means on the depressed end of said declining leg means comprising a first plate secured to the under side of said declining leg means and spaced from the depressed end thereof, a second plate hinged on a horizontal transverse axis to said first plate, said second plate being thereby swingable to supportably engage the under side of said declining leg means between said first plate and the depressed end of said declining leg means, said second plate having a free end arranged to project beyond said depressed end when supportably engaged with the under side of said declining leg means, a screw threaded through said free end of said second plate having a self-leveling floor engaging member on its lower end, and a lock nut on said screw arranged to engage said second plate to lock the screw in a vertically adjusted position.
